UNITED STATES PATENT OFFICE.

EDWARD L. WOOD, OF DETROIT, MICHIGAN.

MEANS FOR FASTENING SOFT MATERIAL TO SHEET METAL.

1,381,154.

Specification of Letters Patent. Patented June 14, 1921.

Application filed May 9, 1919. Serial No. 296,015.

To all whom it may concern:

Be it known that I, EDWARD L. Wood, a citizen of the United States, and residing at Detroit, in the county of Wayne and State 5 of Michigan, have invented a new and Improved Means for Fastening Soft Material to Sheet Metal, of which the following is a specification.

This invention has reference to fastening 10 one or more blocks or pieces of relatively soft flexible material, such as felt, to a piece of sheet metal, such as soft tinned plate. In connecting such parts it is customary to either employ screws or similar devices, 15 which is objectionable on account of the additional expense for labor and material, or to cement the parts together, which is unreliable, particularly where the swab is to be dipped in gasoline or other solvent.

20 In accordance with the present invention, however, the relatively soft block of compressed felt or the like is first perforated to form a hole or cavity of suitable size, the parts are assembled in the desired relation, 25 and the metal is drawn, slitted and bent, by means of a suitable tool, centrally of the perforation to form a plurality of diverging tongues which hook into or about the soft material to firmly bond the latter to the 30 sheet metal. A single fastening thus formed not only secures the parts together tightly against any tendency to separate, but also affords a practical means for preventing relative rotation; the perforation constitutes 35 a vent which is highly desirable for certain purposes, as will be pointed out later. It will be noted, moreover, that the connection requires no extra material, and may be rapidly made at a nominal labor cost.

40 In the drawings, Figures 1, 2, 3 and 4 are sectional views showing different stages of the operation as applied for the purpose of securing a swab to a can cover. Fig. 5 is a perspective view of the preferred tool. Fig. 45 6 is an inside perspective view showing the tongues as slit and bent from the can cover, and Fig. 7 is an inverted plan view of the finished cover and block.

1 indicates a sheet of thin soft metal, in 50 this instance intended as a can cover and provided with the flange suitably threaded for application to a paper or other can, not shown. A sheet or block of felt or the like appears at 2, said block being adapted, 55 when suitably secured to the cover, to form

a swab for which the cover constitutes a hand grip or handle. The soft material is perforated at 3 to form an opening, preferably of cylindrical shape and of considerable size. A suitable tool is shown at 4: in the preferred construction it is of rectangular cross section although it may have a greater or less number of sides, say three or five. This tool is ground to a gradual taper or curvature of about the configuration indicated in the drawing, it being observed that the rectangular or polygonal cross-section is preserved throughout. Near the extreme end, the sides may be plane to form a very small pyramid.

The felt and metal sheet being placed on a suitable die or support 7, perforated at 8 to correspond to the perforation 3 and in alignment with the tool 4, either the tool or die is caused to approach the other, the tool being central to the perforation 3.

The first stage of the operation, that is, the drawing stage, is indicated in Fig. 2 and forms a substantially pyramidal indentation (with the tool shown) of considerable size. As the relative movement continues, the metal is pierced and the sharp edges of the tool slit the sheet radially, and the curved faces simultaneously gradually bend the triangular tongues 9 over—see Fig. 3—until the points strike the felt, after which a further movement for the most part spreads the tongue and embeds the points well into the material. In this latter stage, also, the base portions of the tongues are pressed outwardly into the adjacent soft material to form a rectangular or polygon circumscribed on the opening 3 so that a very rigid holding action against relative rotation is obtained.

The opening 3 is of the greatest importance since it permits the free formation of the tongues, at least up to the stage indicated in Fig. 3, the particular shape which they assume being dependent on the angle between their sides, the stiffness of the metal, and the curvature of the tool. The bending stress may be regarded as being applied successively to very small elements parallel to the corresponding base, and after a given element has swung away from the tool its relation to the next wider element is not again changed (except at the final stage when those parts near the base may be flattened somewhat by the reaction

of the felt). Therefore, the tips of the tongues may be made to pierce the soft material by a substantially radial movement, and a firm gripping is insured. For some purposes more than one fastening may be desirable.

When the device is applied to a cover of a tire patch can, the swab is at times wet with gasoline for cleaning the tube preparatory to the application of a patch thereto. The patches are, of course, normally kept in the can, and when the cover is replaced would be subject to deterioration from the vapor of the gasoline but for the fact that it may readily escape through the vent. This feature is obviously of value generally in venting fastenings.

It is also obvious that the invention may be utilized whether the element 2 is formed integral or in two or more layers of the same or different thicknesses such as the sheets 2' and 2'', Fig. 4; and in such cases the securing of the plurality of sheets together, as distinguished from their attach-

ment to the metal plate, may be the primary object.

Other changes than those indicated may be made without departing from the spirit of the invention, and I do not, therefore, wish to be limited except as indicated by the subjoined claims.

I claim:—

1. In combination, a sheet of metal and a perforated swab of relatively soft compressed material, said sheet of metal having a series of integral tongues struck up within the limits of the perforation in the swab and bent over in hook-like form into the body of the swab.

2. A sheet metal can cover including a sheet metal end and a perforated block of compressed fibrous material attached to one face of the sheet metal end by a plurality of tongues integral with the sheet metal end, said tongues curving into the perforation in said block and diverging from a common center and piercing the fibrous material.

EDWARD L. WOOD.
